UNITED STATES PATENT OFFICE.

MILLARD GILMORE, OF CHICAGO, ILLINOIS.

ELEVATOR FIRE-DOOR.

1,265,075.

Specification of Letters Patent.

Patented May 7, 1918.

Application filed January 21, 1916. Serial No. 73,298.

To all whom it may concern:

Be it known that I, MILLARD GILMORE, a citizen of the United States, residing at Chicago, in the county of Cook and State 5 of Illinois, have invented a certain new and useful Improvement in Elevator Fire-Doors, of which the following is a specification.

My invention relates to an improved elevator fire door construction of the counterbalanced type in which the door consists of 10 two panels vertically movable and connected together so that one panel balances the other, and my invention relates particularly 15 to improved devices for securing the panels together when in their closed position and an improved means of support for the lower panel when in its open position. My invention also provides an improved guiding 20 means for the panels, which guiding means while it is shown in connection with the particular type of door disclosed in the drawings, is also applicable to other types of sliding doors in which it is desirable to 25 reduce the amount of friction of the guides.

The several drawings illustrating my invention are as follows:

Figure 1 shows in elevation my door construction completely assembled.

30 Fig. 2 is a sectional view of one of the vertical guides taken along the line 2—2 in Fig. 1, with the door construction in its open position.

Fig. 3 is a sectional view similar to Fig. 35 2 taken through one of the vertical guides along the line 3—3 in Fig. 1.

Fig. 4 is a sectional view of the upper edge of the upper panel of the door taken along the line 4—4 in Fig. 1.

40 Fig. 5 is a view similar to Fig. 4 showing a section of the lower part of the lower panel of the door taken along the line 5—5 in Fig. 1, and

Fig. 6 is a sectional view of the parts 45 shown in Fig. 1 taken along the line 6—6.

Similar numerals refer to similar parts throughout the several views.

As shown in the drawings, the door construction consists of the upper panel 10 and 50 the lower panel 11 arranged to move vertically in the guides 12 and 13, which guides, as shown more clearly for the guide 13 in Fig. 2, each consists of two angle bars 13^a and 13^b bolted together as shown and to 55 the supporting wall 14 so that the outstand-

ing flange of the angle bar 13^b is substantially parallel with the face of the wall 14 and forms a channel between the angle bar and the wall for guiding one edge of the upper and lower panels. The bolts 15 used 60 to hold the angle bars 13^a and 13^b together have preferably located upon them under the ends of said bolts washers 15^a, which are preferably of any desired material that will yield under the application of high temperature to release the bolts and permit the angle bars 13^a and 13^b to move longitudinally of each other so that distortion of the guides 12 and 13 will not occur before the application of such temperatures. Clearance slots are preferably provided in one or 65 both of the angle bars 13^a and 13^b to receive the bolts 15 to permit this operation to take place.

The upper and lower panels of the door 70 are connected together as follows: Sheaves 16 and 17 are mounted adjacent to the upper portions of the guides 12 and 13 as more clearly shown in Figs. 1 and 2 by means of Z bars 16^a and 17^a, securely held in place by 75 the bolts 18 and 19, which extend through said Z bars and the angle bars beneath them into and through the walls 14. The outstanding flanges of the Z bars form supports for the inner ends of the pivot rods 80 20 and 21 of the sheaves 16 and 17, the outer ends of these pivot rods being supported by bent bars 22 and 23 extending around the sheaves and secured at their ends to the outstanding flanges of the Z bars. 85 Chains 24 and 25 pass around the sheaves 16 and 17 and are secured at their inner ends to brackets 26 and 27 secured to the upper panel 10 and also to the ends of the transverse bar 28 extending across the lower 90 portion of the outer face of said panel between said brackets and said panel. The outer ends of the chains 24 and 25 are connected by tie rods 29 and 30 with the projecting ends of the trucking bar 31 secured 95 to the upper edge of the lower panel 11. This trucking bar preferably consists of an angle bar so that its upper or outstanding flange may fill the slot between the floor and the wall provided for receiving through 100 it the lower panel 11.

When the door is in its open position the outstanding flange of the trucking bar 31 rests upon a supporting bar 32 extending 105 completely across the opening between the 110

guides and having its ends downwardly bent to clear the lower ends of the connections with the tie rods 29 and 30, and these downwardly bent ends are directly supported 5 from the wall 14 by means of bolts 33, suitable spacing blocks 34 being employed to relieve the guides of the strain that might otherwise be brought upon them. When the door is open the upper surface of the outstanding flange of the trucking bar 31 is flush with the surface of the floor and the lower surface of said outstanding flange rests directly upon the supporting bar 32, thus bringing any load placed upon the 10 trucking bar in moving articles on to or from the elevator directly upon the supporting bar instead of causing the trucking bar to take said load. This is a marked improvement over constructions in which the 15 trucking bar is depended upon to take the load, for the reason that the angle forming said trucking bar in such cases must be much heavier, and as a result the opening through the floor for receiving the lower panel must 20 be considerably wider.

As shown in Figs. 4 and 5, the upper edge of the upper panel 10 and the lower edge of the panel 11 are formed into rearwardly projecting flanges 10^a and 11^a respectively 25 provided with apertures through them for receiving the retaining hooks 35 and 36 respectively, which are supported from and rigidly secured to the wall of the building. These hooks are so formed that by their engagement with the flanges referred to the 30 upper and lower edges of the upper and lower panels respectively are held closely to the wall to provide against the possibility of their buckling outward under the application 35 of high temperature.

An important feature of my invention consists in the means employed for securing the two panels of the door together when in their closed position, and the construction 40 employed for this purpose consists of a central latch 37 of bell crank conformation pivoted at 38 to the bar 28 and thus to the lower portion of the panel 10. The horizontally extending portion of the latch forms the 45 handle and the vertically extending portion thereof has formed at its lower end a hook for passing through a corresponding slot in the outstanding flange of the trucking bar 31 so as to securely hold the two panels together 50 when the latch is in the position indicated in Fig. 1. The relation of these parts is also indicated in Fig. 6. In addition to the latch 37 safety latches 39 and 40 are provided, which are pivotally supported at 55 41 and 42 to the lower portion of the panel 10 and provided at their lower ends with hooks similar to the hook on the latch 37, the principal difference being that these safety latches are so disposed that when the 60 latch 37 is in its engaging position indicated 65

in Figs. 1 and 6, the hooks on the safety latches clear the under side of the outstanding flange of the trucking bar by a small amount as indicated in Fig. 1. The safety latches 39 and 40 are connected together by a horizontal bar 43 pivotally secured to them at its ends, and this bar is provided at its middle portion with a slot 44 through which a stud or bolt 45 secured to the latch 37 projects. The slot 44 is so conformed that during the operation of engagement between the latches and the trucking bar if for any reason the panels are not brought sufficiently close together so that the latch 37 engages the trucking bar to retain it in closed position the safety latches 39 and 40 will operate somewhat in advance of the latch 37 so as to provide a measure of safety in this respect that could not be secured by the use of the latch 37 alone. Also when all of the latches 70 are in their locking position indicated in Fig. 1 if for any reason the main latch 37 should fail, the safety latches 39 and 40 are in position to prevent separation of the panels from each other, which might occur 75 if the panels were not held together. The slot 44 is so proportioned that when the latch 37 is rotated around to the left on its pivot 38, the stud or pin 45 moves the bar 43, and thus throws the latches 39 and 40 to 80 their releasing position so that the panels may be freely moved away from each other. As a result of the weight of the handle of the latch 37, all of the latches move to their 85 engaging position under the action of gravity and to prevent movement of the latches too far to the left to properly engage the corresponding slots in the outstanding flange of the trucking bar 31 the inner end of the handle of the latch 37 is made sufficiently 90 wide as indicated at 37^a to engage the top surface of the bar 43 when the latches are in substantially vertical position so that the latches are held at all times in such position 95 as to enter the slots provided for them in the 100 trucking bar.

In connection with elevator doors of the kind under consideration it sometimes occurs that the connecting chains give way, with the result that both panels at once drop 105 to the lower part of the guides, leaving the upper part of the opening into the elevator wall open, and for this condition fire could pass freely through said opening. To provide against this I provide stops 46 and 47 110 on the guides 12 and 13 respectively, which stops consist of flat angle bars secured to said guides and having projecting arms extending into the path of the brackets 26 and 27 respectively and located below said brackets 115 so that the upper panel 10 will be supported in its closed position instead of dropping with the lower panel if for any reason the chains or their supports should break.

As indicated in the drawings, the panels 120

10 and 11 are formed of corrugated iron and at their vertical edges as indicated at 10^b and 11^b outstanding flanges are formed on them to substantially fill the space between 5 the opposite sides of the guideways which are parallel with the plane of the door, the outer edges of these flanges, however, being sufficiently removed from the other flanges of the guide angles to afford the proper 10 clearance to allow for expansion of the door under high temperature. It has been found heretofore that the construction described affords considerable resistance to the operation of the doors on account of the large 15 amount of bearing surface and the rough and uneven surface of the wall forming a part of the guide ways. To eliminate this difficulty and maintain the panels in as nearly as possible the same position in the 20 guide ways, I provide auxiliary guiding means consisting of the bent bars 10^c for the panel 10 and 11^c for the panel 11, these bars being secured near the four corners of each panel and each bar being formed at 25 its outer end as indicated in Fig. 3 so that its bent U shaped end passes around the outer edge of the outstanding flange of the corresponding guide way with just sufficient clearance so that the guide bar may move 30 freely upon said flange. These bars are secured to the panels by suitable bolts as indicated in Figs. 1 and 3, which bolts pass through longitudinal slots therefor in the guiding bars to facilitate proper adjustment 35 of the guiding bars. As a result of the construction of the bars a minimum amount of bearing surface between the guide bars and the guide is used, and since the only bearing surfaces of the guides involved are parts 40 of rolled angle bars, the amount of friction of these bearing surfaces is reduced to a minimum without, however, in any way interfering with the expansion of the panels under high temperature for the reason that 45 the guide bars will either readily bend to permit lateral expansion of the panels or they will slip at their points of connection to the panels as a result of the slots through them referred to.

50 From the above description it will appear that the retaining hooks 35 and 36 coöperate effectively with the upper and lower edges of the top and bottom panels respectively as a result of the manner in which the panels 55 are guided, for by guiding the panels with the accuracy possible by my construction the hooks register better with the openings formed in the edges of the panels to receive them and it is possible to make a closer joint 60 between the edges of the panels and the wall by means of the retaining hooks than would be the case if the panels were comparatively loose in the channels between the angle bar guides and the wall. It will be understood 65 that the panels are made usually of thin

sheet metal, as a result of which if the weight of the upper panel were carried by the retaining hook 35 when the panel occupies its closed position the thin sheet metal would be readily bent from its proper position. This is prevented by the angle bar stops 46 and 47, which carry the weight of the upper panel in its closed position if for any reason the counter balancing connection between the two panels is broken, and in this 75 manner the weight of the upper panel is prevented from coming upon the upper retaining hook 35.

While I have shown my invention in the particular embodiments herein disclosed, it 80 will be understood, however, that I do not limit myself to these exact constructions as I may employ equivalents thereof without departing from the spirit of my invention.

What I claim is:

1. In a door for elevators, the combination of a vertically movable door for closing the opening in a wall, said door being movable downward to open the same and having rigidly secured to its upper edge a 90 trucking bar, and a supporting bar supported clear from said wall and rigidly secured thereto for supporting said trucking bar in its open position for receiving the load that may be placed upon said trucking bar. 95

2. In a door for elevators, the combination of a vertically movable door for closing the opening in a wall, said door being movable downward to open the same and having rigidly secured to its upper edge a 100 trucking bar, and a supporting bar supported clear from said wall and rigidly secured thereto for supporting said trucking bar in its open position for receiving the load that may be placed upon said trucking bar, said 105 trucking bar consisting of an angle bar the outstanding flange of which is supported for substantially its entire length by said supporting bar when said door is in its open position. 110

3. In a door for elevators, the combination of a vertically movable door for closing a doorway in a wall, said door being movable downward through a slot in the floor to open the same and having at its upper edge 115 a trucking bar, and a supporting bar rigidly supported directly from said wall for supporting said trucking bar in its open position flush with the floor for receiving the load that may be placed upon said trucking 120 bar, said trucking bar in its open position closing said slot.

4. In a door for elevators, the combination of a door vertically movable adjacent a doorway through a wall, a trucking bar carried by the upper edge of the door, and a supporting bar carried by the wall outside of said door, whereby said door moves between said wall and said supporting bar, said supporting bar being located at such a 125 130

height on the wall as to support said trucking bar substantially in the plane of the floor when the door is in its open position.

5. In a door for elevators, the combination of a door vertically movable adjacent a doorway through a wall, a trucking bar carried by the upper edge of the door, and a supporting bar carried by the wall outside of said door, whereby said door moves between said wall and said supporting bar, said supporting bar being located at such a

height on the wall as to support said trucking bar substantially in the plane of the floor when the door is in its open position, said trucking bar having an outstanding flange supported throughout substantially its whole length by said supporting bar when the door is in its open position. 15

In witness whereof, I hereunto subscribe my name this 10th day of January, A. D. 20 1916.

MILLARD GILMORE.
